UNITED STATES PATENT OFFICE

2,579,954

TABLET BOX

James H. O'Neil, Syracuse, N. Y., assignor to Continental Can Company, Inc., New York, N. Y., a corporation of New York

Application July 3, 1945, Serial No. 602,965

3 Claims. (Cl. 220—36)

1

The invention relates to new and useful improvements in a tablet box and more particularly a box which can be unlatched by pressing on the rear portion of the cover.

An object of the invention is to provide a tablet box of the above type wherein the side walls of the body are of uniform height, and wherein each side wall is bodily displaced upwardly in the plane of the wall to form a fulcrum point of contact of the side wall with the cover, the fulcrum point being disposed forwardly from the rear wall of the body to permit the rear portion of the cover to be depressed for releasing the cover from a latch at the front of the box.

A further object is to provide an improved and novel tablet box of the type having a hinged cover and latch which can be released by pressing on the rear portion of the cover, in which the cover and the body walls have smooth surfaces unbroken by any indentations or protuberances other than the latch or hinge formations.

Another object is to provide an improved hinge tablet box of the character described which requires a minimum amount of material for accomplishing the results desired.

In the drawings:

Figure 1 is a top plan view of the box with the cover closed;

Figure 2 is a longitudinal sectional view from front to rear centrally through the box with the cover closed;

Figure 3 is a similar view with the cover unlatched;

Figure 4 is a rear view of the box;

Figure 5 is a sectional view at one side of the box;

Figure 6 is a transverse sectional view through a modified form of the body portion of the box; and

Figure 7 is a side view of the modified form of body.

The improved tablet box comprises a body and a cover each having the rear, front and side walls integrally connected to a bottom and top respectively. The body of the box is made from a single piece of metal by die-shaping. The cover is also made from a single piece of metal by die-shaping. There is a floating hinge connection between the cover and the body which permits the cover to move up and down on the body at the hinge connection and a yielding latch at the front of the box for holding the cover closed. Each side wall of the body is of uniform height throughout and is displaced bodily upwardly in

2

the plane of the wall to form a fulcrum point of contact between the side wall and the cover, which point of contact is disposed forwardly from the rear wall of the body so as to permit the rear portion of the cover to be depressed for unlatching the cover from the body.

Referring more in detail to the drawings, the improved tablet box includes a body portion having a front wall 1, a rear wall 2 and side walls 3, 3. A bottom 4 is formed integrally with the bottom portions of these walls.

The box also includes a cover having side walls 5, 5, a front wall 6 and a rear wall 7. A top 8 is formed integrally with these walls of the cover.

15 The cover may or may not be domed upwardly from front to rear but if domed it merges into the side walls 5, 5 of the cover in a substantially straight line, as indicated at 9 in Figure 2.

The cover is secured to the body by a floating hinge. The floating hinge illustrated includes a pintle 10. The rear wall of the cover is provided with a downwardly extending portion 11 which is curved outwardly, then inwardly and upwardly to form a bead 12 in which the pintle is located. The rear wall is cut away at each end of the downward extension 11 as indicated at 13, 13.

20 The rear wall 2 of the body portion is slit vertically along lines 14, 14 and the metal at the outside of the slits is die-shaped so as to provide rearwardly projecting housings 15, 15. The pintle extends into these housings. The housings are of sufficient height so that the pintle is free to move up and down therein to a limited extent. This is generally referred to as a floating hinge and is shown and described more in detail in the patent granted to Louis Hermani on September 30, 1941, No. 2,257,682.

25 The front wall of the body portion is provided with an outwardly extending detent 17 which is adapted to engage a recess 16 formed in the front wall of the cover. This serves as a yielding latch for securing the cover in closed position.

30 The side walls of the body are of substantially uniform height from the front wall to the rear wall of the body and are arched bodily upwardly in the plane of the wall. As shown in Figure 1, the bottom 4 of the box which is formed integrally with these side walls 3 is likewise arched upwardly from front to rear. This arching of the side walls as shown in Figures 1 to 7 provides a curved upper edge for each side wall. This upper edge is curved upwardly from the front 35 and rear walls to an intermediate high point.

3

The curved edge of the side walls is indicated at 18 in Figures 2 and 3 and the high point is located at 19. This high point is forwardly of the rear wall of the body but nearer said wall than the front wall. This will form a relatively small point of tangential contact with the straight portion 9 of the cover along the side walls 5, 5 of the cover.

This fulcrum point of contact between the cover and the body of the box when the cover is closed is so positioned that the rear portion of the cover top is spaced above the rear wall of the body. At this time the cover is latched and the pintle 12 is in contact with the upper wall of the housing 15. This prevents the cover from moving downwardly at the front if pressure is applied thereto incident to the stacking of the boxes one on another. When pressure is applied at the rear portion of the cover, the pintle can move downwardly. This will allow the cover to turn on the small contacting surface which functions as a fulcrum for causing the latch to be released.

It is noted that the rear wall is shown as of substantially the same height as the side walls and likewise the front wall is of substantially the same height as the side and rear walls. When the walls are all substantially the same height and uniform in height, then the height of the walls relative to the thickness of the pellets contained in the box may be reduced to a minimum and the pellets will be confined thereby. When the side walls are bodily arched upwardly and the cover wall thereabove is straight, there is sufficient clearance between the top of the cover and the rear wall so as to permit the rear portion of the cover to be depressed sufficiently to release the latch. The floating hinge is so constructed and the parts thereof disposed so as to permit this unlatching movement.

As shown in Figures 6 and 7, the body includes a rear wall 20 which is similar in construction with the rear wall 2, as shown in Figures 1 to 4. It also includes a front wall of similar construction and a bottom 21 which is formed integral with the front, rear and side walls. The side walls 22, 22 and a portion of the bottom wall 21 is displaced upwardly in the plane of the walls so that the side wall is arched bodily from front to rear in an upward direction. The bottom of the box is straight from front to rear except at the portions 23, 23, where it is arched to conform to the curvature of the bottom edge of the side walls. Otherwise, the box is of the same construction as shown in Figures 1 to 4 and the cover can be released from its latch through the fulcrum rest on the side walls and by pressing on the rear of the cover. While in the drawings, the arch of the side walls is shown as curved, it will be understood that the side walls may be straight for providing the intermediate high point 19 if so desired.

It is obvious that many changes in the details of construction may be made without departing from the spirit of the invention as set forth in the appended claims.

I claim:

1. A tablet box comprising a body and a cover, each having rear, front and side walls integrally connected to a bottom and top respectively with

4

the cover walls surrounding the body walls all of said body walls being of substantially the same height throughout, a hinge connecting the cover to the body so as to permit the cover to move up and down on the body at the hinge connection, a yielding latch connection at the front of the box, each side wall of the body being displaced bodily upwardly in the plane of the wall so as to provide an upper edge which is arched upwardly to form a fulcrum point of contact between the upper edge of the side wall and the cover said fulcrum point being disposed forwardly from the rear wall of the body whereby the latching of the cover to the body may be released by pressure applied to the rear of the cover.

2. A tablet box comprising a body and a cover, each having rear, front and side walls integrally connected to a bottom and top respectively with the cover walls surrounding the body walls all of said body walls being of substantially the same height throughout, a hinge connecting the cover to the body so as to permit the cover to move up and down on the body at the hinge connection, a yielding latch connection at the front of the box, each side wall of the body being displaced bodily upwardly in the plane of the wall so as to provide an upper edge which is arched upwardly to form a side wall fulcrum for the cover disposed forwardly from the rear wall of the body whereby the latching of the cover to the body may be released by pressure applied to the rear of the cover, the bottom of the box being curved upwardly to conform to the curvature of the upper edge of the side walls.

3. A tablet box comprising a body and a cover, each having rear, front and side walls integrally connected to a bottom and top respectively with the cover wall surrounding the body walls all of said body walls being of substantially the same height throughout, a hinge connecting the cover to the body so as to permit the cover to move up and down on the body at the hinge connection, a yielding latch connection at the front of the box, each side wall of the body being displaced bodily upwardly in the plane of the wall so as to provide an upper edge which is arched upwardly to form a side wall fulcrum for the cover disposed forwardly from the rear wall of the body whereby the latching of the cover to the body may be released by pressure applied to the rear of the cover, the bottom of the body in the region adjacent the side walls being curved to conform to the upper edge of the side walls, the intermediate portion of the bottom lying in a plane containing the bottom edge of the front and rear walls.

JAMES H. O'NEIL.
